Term of patent 14 years

(Cl. D52—6)

FIG.1

FIG.2

FIG.3

FIG.4

FIG. 1 is a front view of an edgewise panel meter, showing my new design, the horizontal bar below the scale graduations being shaded to represent contrast; the scale graduations being shaded to represent contrast;

FIG. 2 is a bottom plan view thereof with a portion of the conventional rectangular casing broken away for convenience of illustration;

FIG. 3 is an end view thereof, the housing in broken lines being omitted for convenience of illustration; and

FIG. 4 is an enlarged detail sectional view taken along the line 4—4 of FIG. 1.

The essential features of the design reside in the portions shown in full lines.

I claim:

The ornamental design for an edgewise panel meter, as shown and described.
